[57] CLAIM

The ornamental design for an antenna connector, as shown and described.

DESCRIPTION

FIG. 1 is a top and right side perspective view of my antenna connector showing my new design. The broken line showing is included for the purpose of illustrating environmental elements only and forms no part of the claimed design;

FIG. 2 is a right side elevational view thereof, the left elevational side being a mirror image;

FIG. 3 is a top plan view thereof; and,

FIG. 4 is a bottom plan view thereof.

FIG. 1

FIG. 2

FIG. 3

FIG. 4
